TYPEWRITING MACHINE

William A. Dobson, Wethersfield, Conn., assignor
to Underwood Elliott Fisher Company, New
York, N. Y., a corporation of Delaware

Application October 22, 1936, Serial No. 106,973

3 Claims. (Cl. 197—27)

This invention relates to portable typewriting machines.

Desirable properties or virtues in portable typewriting machines include compactness, that is, minimum over-all dimensions so that the portable typewriter can be packed in brief-cases, suit-cases, valises, or other convenient carrying containers; lightness, so that the addition of the portable typewriter to the baggage or luggage will not be too burdensome an encumbrance to anyone, even to young students; strength and durability; lightness and smoothness of key-lever action and sufficient power in the type impact to produce a number of clear carbon copies; freedom from undue canting of the keys when the typewriter is actuated so that the fingers do not slip off the keys while typing; accessibility of all the parts for manufacture, adjustment, or repair; sharp, clear, and regular type impressions; saleability; low-cost manufacture; visibility; a standard keyboard having a full complement of 44 keys and 44 coating type-bars; platen case-shifting for upper and lower case type; a printing line having sufficient letter-spaces to utilize standard business letter-head copy sheets or legal-size paper; and general attractiveness and pleasing appearance of the typewriter.

In approaching the problem of creating a portable typewriter that will have the above enumerated virtues or desirable qualities, it is evident that the minimum width possible is predetermined by the width of a standard typewriter keyboard with standard type-faces, and the length of a platen requisite to accommodate lines of sufficient length to permit the use of the legal and business copy sheets now customarily used. In procuring compactness of a portable typewriter reduction in the height and reduction in the front to rear dimension may be made so long as the reductions do not impair or detract substantially from other desirable qualities or virtues enumerated above, so therefore the compactness of the type-action, provided that other desirable properties of the typewriter are not sacrificed or impaired, may be directly related to compactness of the typewriter as a whole. The present invention is directed to the provision of improvements in type-actions with a view toward their utility in portable typewriters, more especially in reducing the height of the typewriter and in reducing its front to rear dimension.

The present invention provides in a portable typewriter the combination with an array of

type-bars pivotally mounted near the bottom of the machine to swing toward the platen rearwardly and downwardly from an initial inclined position extending forwardly and upwardly, of a set of key-levers that are fulcrumed on pivots which lie in a straight line substantially in the transverse vertical medial plane of the typewriter and substantially in the horizontal medial plane of the typewriter in front of and underneath the array of quiescent type-bars and that 5 10 15 20 25 30 35 40 45 50 55 60 65 70 75 80 85 90 95 100 105 110 115 120 125 130 135 140 145 150 155 160 165 170 175 A modification of the invention involves the provision of sub-levers pivotally mounted on a reinforcing crosspiece below and adjacent the type-bar comb, each sub-lever having an arm depending vertically from the fulcrum point and an arm inclined rearwardly and upwardly and

provided with an inclined slot for engaging the key-lever side pin. This construction permits of the use of somewhat shorter key-levers than the other form of sub-levers. The positions of the key-lever side pins may be varied and the shape of the sub-levers, for key-levers of different rows and different distance from the center. In this form of the invention a recoil spring is fastened intermediately on the vertical arm and connected with a lever arm formed on the end of the corresponding actuating key-lever.

The positioning of the key-lever pivots in the transverse medial vertical plane underneath the forwardly and upwardly inclining quiescent type-bars permits the full height of the typewriter to be substantially measured by the horizontal planes through the tops and the bottoms of the inclined quiescent type-bars, because the elimination of the necessity for the space underneath the type-bars for an arrangement of key-levers permits the type-bar pivots themselves to be placed practically at the bottom of the typewriter, so that by using short type-bars and inclining them at a low pitch, a typewriter may be constructed that is easily slipped into a brief-case because of its small height, but without sacrificing any of the requisite or desirable virtues in a portable typewriter. The positioning of the key-lever pivots substantially in the medial horizontal plane provides ample room for the vertically arranged sub-levers and for key-levers of sufficient length that they can actuate the type-bars with a light, smooth touch on the keys and without undue canting of the key-levers to such an inclination that the finger of the typist might slip off the front edge of a key. In either form of the invention the crosspieces form a strong reinforcement of the frame of the machine.

Other features and advantages will hereinafter appear.

In the accompanying drawings:

Figure 1 is a left side elevation partly in section and illustrating one form of the invention, the top, bottom, front, and rear of the complete typewriter being shown in broken lines.

Figure 2 is a view out of Figure 1 and enlarged, but with additional key-lever sub-levers to illustrate the four forms used for coaction with side pins on key-levers in the different key-banks.

Figure 3 is another form of the invention in side elevation.

Figure 4 is a left side elevation partly in section and illustrating one form of the invention, the top, bottom, front and rear of the complete typewriter being shown in broken lines.

Figure 5 is a plan view, parts broken away, of the form of the invention shown in Figure 1. The left key-lever shown is at the right of the center of the machine.

A portable typewriter has a casing 10, a platen 11 at the rear, and a rearwardly and upwardly inclined type-bar segment 12, having an arcuate pivot rod 13, on which are mounted type-bars 14, adapted to strike downwardly and rearwardly on the platen 11.

From the bottom of each type-bar 14 depends an arm 15 to which is connected a link 16 having an angled bend 17 therein. The links 16 connect with the other part of the type-action as will be hereinafter more fully described.

The typewriter shown has the standard keyboard having 44 keys 18, arranged in four rows or banks, each row toward the rear being higher

than the row immediately in front, as clearly shown in Figure 1.

Four rows of key-levers 19 likewise have horizontal forwardly and rearwardly extending parts positioned at different heights in co-relationship with the keys 18 which they support. All of the key-levers 19 are pivoted on a horizontal straight pivot rod 20, fixed in a cross-piece 21, mounted in the sides of the frame 22 of the machine. This pivot rod 20 is preferably positioned substantially in both the horizontal medial plane of the typewriter and the transverse vertical medial plane. By reference to Figures 1 and 4, it is evident that the locus of the pivot rod 20 is also below and to the rear of the heads 23 of the central type-bars 14 in their quiescent or inoperative position reclining on a type-bar rest 24.

The fact that this straight line defined by the intersection of the horizontal and vertical medial planes of the typewriter is the locus of the pivot points of all of the four banks of key-levers is the first step in the discovery of an answer to the problem of how to construct the most compact, low-cost portable typewriter without sacrifice of the good qualities possessed by a standard typewriter. This pivot locus provides for key-levers 19 of sufficient length that the depression of keys 18 does not cause so much canting of the keys 18 that there is danger of a finger slipping off the front of a key during typing. This location of the reinforcing and supporting crosspiece 21 in the frame 22 is central and conduces to the strength, lightness and rigidity of the machine. The pivot rod 20 is also sufficiently high that there is plenty of room for the depression of the front row of key-levers 19. The location of the pivot rod 20 under the type-bars 14 also permits the location of the keys near the quiescent inclined type-bar heads 23 conducing to a minimum dimension, front to rear, for a portable typewriter having a standard keyboard and type-bars of ample length to afford the requisite velocity of type-bar impact on the platen 11, as well as conducing to a minimum height measured by an inclined type-bar because the need for space beneath the bottoms of the type-bars 14 for the key-levers 19 is entirely eliminated.

Each key-lever 19 is held at the rear in a spacing and guide slot 25 formed in the crosspiece 21.

At the side of each key-lever 19 is mounted a laterally projecting pin 26. Referring to Figures 1, 2 and 5, this pin 26 contacts and overlies an inclined camming arm 27.

Each key-lever 19 is guided at the front in slots 28 in the comb 29, secured in the frame 22 of the typewriter. Each lateral pin 26 contacts the upper edge of the camming arm 27 at a point considerably to the right of a straight transverse pivot rod 30 on which the sub-levers 31 are pivoted in vertical slots 32 in the crosspiece 33, mounted in the sides of the frame 22 at the bottom of the typewriter below and in front of the crosspiece 21. Each sub-lever 31 has a nearly vertical but rearwardly inclined arm 34, provided with a pivot hole 35, in which is secured the forward end of a link 36. Restoring springs 36 may also be secured to the arms 34 and to a cross-piece 37, mounted in the frame 22 of the typewriter. Inasmuch as the pivot rod 20 is to the rear of and above the pivot rod 30, when and as a key 18 is canted down, the associated pin 26 mounted on the key-lever 19 moves towards the sub-lever pivot 30 and so lessens the effective leverage of the camming arm 27, thereby, in 75

conjunction with the coil spring 36, relieving the harshness which would otherwise make the key-lever action unsatisfactory to the average typist.

As is shown in Figure 2, sub-levers 31 are provided with four differently inclined camming arms 27 adapted to snugly engage pins 26 on four different rows of key-levers 19 in a standard keyboard.

Referring to Figures 1 and 5, a universal bar 38 is supported at either end by a depending arm 39, pivotally mounted at the bottom on a transverse rod 30 immediately in front of and in contact with the front edge of the upstanding arm 34 of each sub-lever 31.

Referring now to Figures 3 and 4, a modified form of sub-lever 40 has an upper rearwardly inclined arm 41, having a central upwardly and rearwardly inclined slot 42. The sub-levers 40 are pivoted in spacing and guiding slots and on a straight rod 43, mounted on the rear inclined edge of a crosspiece 44 mounted in the sides of the frame 22.

A spring 45 is tied to an ear 46, formed on the rear of the sub-lever 40, and to an arm 59, depending from the key-lever 19. The lower front edges of the sub-levers 40 contact and actuate a universal bar 47, mounted on arms 48, depending from the outer ends of rock-shaft 49.

It is obvious that as a key-lever 19 is depressed the arm 15 and sub-lever 40 move apart and increase the tension on the key-lever 19 to a maximum at the end of a stroke, thereby cushioning the finger and making a pleasant touch.

Variations may be resorted to within the scope 35 of the invention, and portions of the improvements may be used without others.

Having thus described my invention, I claim:

1. In a portable light-duty typewriting machine having a platen and a full complement of 40 swingable type bars having upper and lower case types; a type bar fulcruming segment inclining forwardly and downwardly from the platen substantially to the bottom of the machine so that the type bars in their rest positions incline upwardly and forwardly toward a level substantially 45 no higher at their type ends than the top of the platen, and strike downwardly and rearwardly upon the platen, a system of key levers presenting a plurality of transverse key rows substantially no higher than the level of the top of the platen, said key levers being swingable about a common transverse fulcrum axis disposed forwardly of the type bar fulcruming segment in close proximity to the central type-bars at rest, 50 a system of sub-levers having a common transverse horizontal fulcrum axis forwardly of and below said key lever axis, said sub-levers presenting substantially uniform upright type-bar-operating arms reaching above the key levers, a 55 system of pull links individually connecting said sub-lever arms to corresponding type bars and reaching across the system of key levers and beneath the fulcrum axis thereof, a pin and single-sided cam-edge connection between each key 60 lever and a corresponding sub-lever whereby the latter is driven by the key-lever in the printing-stroke of said key-lever, and a system of springs directly connected to the sub-levers to restore 65

any operated type bar together with its sub-lever and key lever.

2. In a portable light-duty typewriting machine having a platen and a full complement of swingable type bars having upper and lower case types; a type bar fulcruming segment inclining forwardly and downwardly from the platen substantially to the bottom of the machine so that the type bars in their rest positions incline upwardly and forwardly toward a level substantially no higher at their type ends than the top of the platen, and strike downwardly and rearwardly upon the platen, a system of key levers presenting a plurality of transverse key rows substantially no higher than the level of the top of the platen, said key levers being swingable about a common transverse fulcrum axis disposed forwardly of the type bar fulcruming segment, a system of sub-levers having a common transverse horizontal fulcrum axis forwardly of and below said key lever axis, said sub-levers presenting substantially uniform upright type-bar-operating arms, a system of pull links individually connecting said sub-lever arms to the corresponding type bars, each sub-lever also presenting a single cam edge extending forwardly from the type-bar-operating arm and engaged by a pin or the like of the corresponding key lever, whereby the key lever in its printing stroke drives said sub-lever, and a system of springs directly connected to the sub-levers to restore any operated type-bar, together with its sub-lever and key lever, the several cam edges and companion pins having different dispositions consonantly with uniform printing stroke depressions of the 35 keys of the several key levers and different extents of swing of the type bars to the platen.

3. In a portable light-duty typewriting machine having a platen and a full complement of swingable type bars having upper and lower case types; a type bar fulcruming segment inclining forwardly and downwardly from the platen substantially to the bottom of the machine so that the type bars in their rest positions incline upwardly and forwardly toward a level substantially 45 no higher at their type ends than the top of the platen, and strike downwardly and rearwardly upon the platen, a system of key levers presenting a plurality of transverse key rows substantially no higher than the level of the top of the platen, said key levers being swingable about a common transverse fulcrum axis disposed forwardly of the type bar fulcruming segment in close proximity to the central type bars at rest, a system of sub-levers having a common, transverse, horizontal fulcrum axis disposed forwardly of said key lever axis and presenting upstanding type operating arms reaching above the key levers, a system of pull links individually connecting said sub-lever arms to the corresponding type bars 60 and reaching across the system of key levers and beneath the fulcrum axis thereof, a pin and cam connection from each key lever to the companion sub-lever, and a system of springs directly connected to the sub-levers to restore any operated 65 type bar together with its sub-lever and key lever.

WILLIAM A. DOBSON.
